EDWARD B. HESS, OF NEW YORK, N. Y., ASSIGNOR TO ROYAL TYPEWRITER COMPANY,
OF HOBOKEN, NEW JERSEY, A CORPORATION OF NEW JERSEY.

WRITING-MACHINE.

946,359.

Specification of Letters Patent. Patented Jan. 11, 1910.

Application filed November 15, 1905. Serial No. 287,489.

To all whom it may concern:

Be it known that I, EDWARD B. HESS, a citizen of the United States, residing in the borough of Brooklyn, city of New York, State of New York, have invented certain new and useful Improvements in Writing-Machines, of which the following is a specification.

This invention comprises ribbon mechanism, particularly applicable to front stroke or visible writing machines, and consists in various novel features of construction and arrangement hereinafter set forth in detail.

15 The drawings show one embodiment of the invention in a form constructed by me and which experience has demonstrated to be practical and efficient.

Figure 1 is a horizontal section, parts being omitted, showing the manner of mounting and driving the ribbon bobbins; Fig. 2 a transverse section showing the same and other parts; and Fig. 3 a detail plan showing the ribbon, its side guide-rollers and the vibrator; Fig. 4, a detail perspective view showing one of the ribbon driving gears and its shaft having a special bearing or seat for the ribbon bobbin; Fig. 5, a transverse section through the shaft showing a device for retaining the bobbin on the shaft; Fig. 6, a detail perspective view showing another form of seat for the ribbon bobbin, and Fig. 7, a similar view showing the ribbon bobbin hub in place upon its seat, the flanges of the bobbin being omitted; Fig. 8, a view similar to Fig. 7 showing a different form of bobbin seat with the hub of a bobbin mounted thereon and having a latch for locking it; Fig. 9, 40 a longitudinal vertical section on the line 9, 9, of Fig. 1 showing, however, the ribbon vibrator, carriage and associated parts; Fig. 10, a similar view illustrating some modifications in construction; Fig. 11, a 45 vertical longitudinal sectional view indicating an organization adapted for a polychrome ribbon and capable of three adjustments, one for each color and one for stencil work; Fig. 12, a detail front elevation in rear of the line 12, 12, in Fig. 11; Fig. 13, a detail side elevation from the left hand side of Fig. 12; Fig. 14, shows the variable leverage ribbon vibrating devices in a position different from that shown in

Fig. 11, and Fig. 15 shows them in the position for stencil work.

Mounted between the side plates of the machine is a cross plate or frame a (Figs. 1, 2, 9) that has a bearing at a' for a shaft a^2 having a pinion a^3 meshing with a gear a^4 formed on the spring drum. The gear a^3 is connected with its shaft through a ratchet and pawl, or other clutch device of appropriate construction, a^5 , so that as the carriage moves, in the operation of printing, and the spring drum makes successive increments of revolution, the shaft a^2 is driven in a direction to feed the ribbon; but when turned in reversed direction as when the operator winds the ribbon from one spool to the other, the shaft revolves independently of pinion a^3 . On the front end of the comparatively short shaft a^2 , geared, as described, directly to the spring drum, is a bevel pinion a^5 meshing with a bevel gear b , operatively connected with the transverse ribbon actuating shaft b' . The gear b is carried by a sleeve b^2 held against movement longitudinally of the shaft by a bifurcated plate b^3 attached to the cross plate a . Suitable cranks are to be applied to the ends b^4 of the shaft, outside of the casing, by which it may be rotated to wind the ribbon or shifted endwise to operatively connect either bobbin with the ribbon feeding devices. The cross plate a is located considerably below the top of the machine and somewhat adjacent the base thereof; and, upon it, suitably adjacent the side plates of the machine, are bearings or housings c , c' for driven shafts c^2 , c^2 upon which, as will be presently described, the ribbon bobbins are directly mounted. The rear end of each such shaft carries a bevel gear c^3 that meshes with a bevel pinion c^4 fixed on the endwise movable shaft b' in such position that when the shaft is shifted to the left, the bevel gears c^3 , c^4 for driving the left hand ribbon bobbin are thrown into operative engagement, and when shifted to the right these bevel gears pass out of engagement and those toward the right hand side of the machine, for driving the right hand ribbon bobbin, are brought into operative engagement. The axes of the shafts a^2 , b' , c^2 , c^2 are all in the same horizontal plane. The ribbon bobbin shafts carrying the driving gears c^3 project forward from the bearings

(c, c') and are in Fig. 4 shown as of angular cross section, the cross section as illustrated being hexagonal. The hub of the ribbon bobbin is correspondingly apertured so that when slipped into place upon the shaft it has an interlocking connection therewith that insures its rotation. To prevent accidental disengagement of the bobbin from its shaft, I may, as indicated in Figs. 4 and 5, place a ball spring-latch c⁵ transversely in the angular portion of the shaft which, while retaining the bobbin normally in place, permits of its ready disengagement and replacement. As shown in Figs. 6 and 7, the forward end of the bobbin shaft may be formed with longitudinal ribs c⁶, and the hub c⁷ of the ribbon bobbin be correspondingly formed to fit thereon: or, as shown in Fig. 8, the ribbon bobbin hub c⁷ may have a cylindrical bore and carry a latch c⁸ operating through an aperture in the hub to engage the recesses formed in the shaft.

C, C, represent the ribbon bobbins and c^x the ribbon traveling, as hereinafter described, from one bobbin to the other. The shaft b' has fast upon it an enlargement or sleeve b⁵ with an annular groove thereon in which are located the arms b⁶ projecting up from a plate b⁷ pivoted upon the cross plate a and having in its front end a roller coöperating with cam recesses b⁸ in the edge of an arm b⁹ pivoted on the plate a and drawn against the roller on the end of arm b⁷ by a spring b¹⁰. In shifting the ribbon driving shaft b' endwise to drive either bobbin from the spring drum, the gears c³, c⁴ will not always be in position to permit of their proper meshing. In such case, the roller of the arm b⁷ will rest upon the inclined wall of one of the cam recesses b⁸; and when the shaft has been rotated sufficiently to bring the bevel gear c⁴ into proper relation with the gear c³ on the bobbin shaft, the spring pressure exerted by arm b⁸ will be sufficient to carry the shaft endwise and bring the gears into complete operative engagement. In Fig. 2, the type-bar segment is indicated at D. It may be of any appropriate construction. The disposition of the ribbon bobbins below the top plate and adjacent the side walls is such as to leave clearings for the assemblage of type bars and their supports and mechanism for operating them. Such type bar operating devices may be of the character shown in various Letters Patent heretofore granted to me as well as in pending applications, as for instance, U. S. Letters Patent No. 700,687, May 20, 1902.

In Fig. 2, the ribbon vibrator d of usual construction is shown as mounted upon a vertical support d' bolted to the front face of the type bar segment D. The axes of the ribbon bobbins are disposed longitudinally of the machine and the ribbon extends

from the outer side of each bobbin vertically or substantially so over idler roller-guides e appropriately mounted at the top of the machine adjacent its sides.

As seen in Fig. 3, the ribbon vibrator d through which the ribbon passes is in a transverse line but slightly in rear of a transverse line passing through the idler roller guides. The outer surfaces of the roller guides over which the traversing ribbon passes are preferably placed in a vertical line lying midway between the hub of the ribbon bobbin and the maximum diameter due to the ribbon wound thereon. This is for the purpose of reducing to a minimum the maximum angularity of the ribbon as it passes to or from the bobbin over the outer surface of the idler roll.

The guide rolls e have their axes inclined to the axis of the platen, the point of conjunction of lines passing through the axes of these rolls being in the center of the machine at a point in front of the platen. Experience has demonstrated that with this arrangement of bobbins and roller guides the ribbon will run freely through the vibrator slots without strain and with no distortion and will readily assume the quarter turn position between the vibrator slots and the respective idler rolls. In the space above the shaft b' and between the vertically disposed parts of the ribbon C^x extending from the bobbins to the idler guides, may be arranged the trough-like assemblage of forwardly extending type bars characteristic of a front stroke machine. This arrangement of type bars, however, being well understood, it has not been deemed necessary to illustrate them or the platen against which they impinge in the operation of writing.

Fig. 9 shows more of the organization of a complete machine. The platen, type-bar segment and type-bars are, however, omitted because unnecessary for the full illustration of this invention. The carriage, of which f is the front rail, is shifted about the axis f' by means of the key-lever f², the construction in this regard being well understood. Any appropriate carriage shift mechanism may be used. As shown the parts are in normal position. The ribbon vibrator d has a downward extension d² pinned at its lower end to the elongated forwardly extending arm g of a bell-crank lever pivoted at g' at the bottom of the carriage, and having a short downwardly extending arm g² to the end of which at g³ is pivoted a link g⁴, which, when the parts are in the normal position shown, inclines forwardly and upwardly to its point of connection g⁵ with the upwardly extending arm h of a bell-crank lever located centrally of the machine, pivoted on an axis h' beneath plate a, and having a forwardly projecting arm h². The end of the latter arm

has pivoted to it the upper end of a pendent link h^3 whose lower end is pivoted to the front end of an arm h^4 extending from the universal bar U rearwardly to its rock-shaft U' . I is the carriage rack-bar engaging pinion i on shaft of escapement wheel i' . The usual escapement pawl i^2 , pivoted at i^3 , extends below its pivot and receives through an aperture a threaded link-bolt i^4 having adjustable nuts, one bearing against each side of the end of the pawl. This link-bolt is jointed to a link i^5 pivoted to the bell crank-arm h below the pivotal connection therewith of the link g^4 . The connection g^3 of link g^4 with the ribbon vibrator bell-crank is normally the same distance below a horizontal line passing through joint g^5 as it is above said line when the carriage is shifted and the ribbon vibrator bell-crank rises with it. When a printing key-lever F is depressed the universal bar U is carried down drawing down link h^3 and throwing bell-crank arm h forward. This operates the escapement pawl i^2 and lifts the ribbon vibrator to carry the ribbon in front of the printing point. The same operations occur in the same way when the shift key is depressed (the carriage being then raised) and a printing key-lever F' is operated. Of course springs are to be suitably applied where required to return, or assist in returning parts to normal position. In Fig. 9 F' is the shift key-lever spring applied adjacent the pivot thereof.

Fig. 10 shows substantially the same construction as Fig. 9, there being only minor modifications, as follows: A coiled spring F^2 extending from cross plate a is applied to the shift key lever; a large gear is carried by the ribbon feed shaft a^2 and a small gear or pinion by the spring drum; and the link bolt i^5 connected with the escapement pawl runs direct to the upright arm h of the bell crank. In this figure the support of the ribbon vibrator is not indicated.

Fig. 11 shows an organization having the general scheme of arrangement already described with additional material features of construction, consisting primarily in variable leverage devices adapted to impart different ranges of throw or vibration to the ribbon (which may now be polychrome and for the special arrangement shown bi-chrome), to bring, in either position of the platen different zones of the ribbon, of unlike color, opposite the printing point, and also to leave the ribbon entirely out of action when the machine is being used to prepare stencils for mimeograph work. In this construction the link h^3 of Figs. 9 and 10 is replaced by link j pivoted to arm h^4 and having at the top a cross pin j' adapted to engage different notches j^2 , j^3 in the arm h^2 of bell-crank lever h , h^2 , at different distances from the axis h' thereof, or to be thrown entirely out of engagement with said arm for stencil work. The means shown for accomplishing these operations or adjustments are as follows: On a rock-shaft k below the arm h^4 is attached an arm k' that stands in front of the universal bar and at its upper end extends rearwardly above such bar and under the cross-piece j' of link j , and has projecting lugs or pins j^4 between which the link j lies. Near the end of the rock-shaft k and, as shown, at the left hand side of the machine, is attached an upwardly extending arm k^2 to the end of which is attached a link k^3 pivoted at its forward end to an upright lever k^4 at the side of the keyboard. This lever is adapted to stand in three positions to which it is readily adjusted by the operator and which are determined by engagement of a pin on the side of the lever with either one of three depressions or notches m , m' , m^2 , in a plate spring fastened at its front end to the frame of the machine. When this lever is in the position shown, in which the pin thereon engages notch m the cross bar j' of link j , lies in notch j^2 of bell-crank arm h^2 which is nearest the axis of the bell-crank, and consequently when a printing key-lever is depressed, in either position of the platen, a maximum throw is imparted to arm h of the bell crank h , h^2 , and the lower band or zone of color of the ribbon is projected in front of the printing point. When lever k^4 is adjusted to bring the projection thereon into notch m' of the plate spring, the link j is drawn forward and the cross pin j' thereof is brought into notch j^3 of bell crank arm h^2 , the result being that the leverage operating upon arm h^2 is increased and a shorter throw is imparted to arm h sufficient to bring opposite the printing point the upper zone of color of the ribbon; and when notch m^2 of the plate spring is engaged by lever k^4 link j is entirely out of operative engagement with bell crank arm h^2 . The ribbon vibrator will now remain at rest and the type may, for stenciling work, be brought to the printing point on the platen without the ribbon intervening. The three conditions described are shown, respectively, in Figs. 11, 14 and 15. A plate spring j^x tends to retain the cross pin j' in the respective notches j^2 , j^3 . Since the ribbon vibrator bell-crank has variable throw, due to variable lever connections, or no movement at all, it is not practicable to use it to operate the carriage escapement pawl. I therefore pivot on the axis or shaft h' , on which is pivoted the bell crank h , h^2 , a second bell-crank n , n' and connect its forwardly extending arm n , by a link n^2 to the arm h^4 (that is to the universal bar U). The upper end of arm n' of this bell crank is connected by bolt link i^6 with the rocking escapement plate i^2 .

In Fig. 9, I have indicated, in dotted lines, 130

the segment D, one of the center type bars T pivoted therein and the platen P for the purpose of giving a general idea of the relation of these parts in the special embodiment 5 of the invention illustrated.

I claim as my invention:

1. In a visible writing machine, the combination with a shifting carriage and ribbon vibrator, of a ribbon vibrating lever 10 rocking about a fixed axis, actuating devices adapted to be connected at different distances from the axis of said lever to thereby afford a variable leverage and consequent variation of movement to bring different parallel 15 zones of the ribbon opposite the printing point and means located in front of the type bars for controlling, at will of the operator, the point of engagement of such operating devices with the lever.

2. In a visible writing machine, the combination with a shifting carriage and ribbon vibrator, of a ribbon vibrating lever arranged longitudinally of the machine and 20 rocking about a fixed axis, actuating devices adapted to be connected at different distances from the axis of said lever to afford variation of movement of the vibrator to bring different parallel zones of the ribbon opposite the printing point and comprising 25 an arm swinging in a vertical plane parallel with that in which said lever lies and having means for engaging said lever, and means located at the front of the machine for controlling, at will of the operator, the 30 point of engagement of such operating devices with the lever.

3. In a visible writing machine, the combination with a shifting carriage, ribbon vibrator and bell crank lever pivoted upon 35 the carriage and connected with the ribbon vibrator, of a bell crank turning about a fixed axis, having an upwardly extending arm connected to the first named bell crank and a horizontally extending arm, actuating 40 devices operating upon the latter arm and means whereby such actuating devices may at will be applied to said arm at different distances from its axis to thereby afford a variable leverage and consequent variation 45 of throw of the ribbon vibrator.

4. In a visible writing machine, the combination of a shifting carriage, a ribbon vibrator, a bell crank lever pivoted on the carriage and having a laterally extending 50 arm connected to the vibrator, a second bell crank turning about a fixed axis on the frame and having a laterally extending arm and an upwardly extending arm, a link connection extending from the latter arm to the downwardly extending arm of the first named bell crank lever, the point of connection between the latter arm and link being, substantially, the same distance below a horizontal line passing through the connection 55 between the link and the arm of the second

named bell crank when the carriage is in normal position as said point of connection is above such horizontal line when the carriage is shifted upwardly, actuating devices for operating the second mentioned bell 70 crank and means whereby they may be applied to the laterally extending arm of said bell crank at different distances from the axis thereof, for the purpose described.

5. In a visible writing machine, the combination of a vertically shifting carriage, a ribbon vibrator, a bell crank lever pivoted on the carriage and having a laterally extending arm connected to the vibrator, a second bell crank turning about a fixed axis 80 on the frame and having a laterally extending arm and an upwardly extending arm, a horizontally disposed link connection extending from the latter arm to the downwardly extending arm of the first named bell crank 85 lever, the point of connection between the latter arm and link being, substantially, the same distance below a horizontal line passing through the connection between the link and the arm of the second named bell crank 90 when the carriage is in normal position as said point of connection is above such horizontal line when the carriage is shifted upwardly, actuating devices for operating the second mentioned bell crank and means under the control of the operator located in front of the type bars whereby such actuating devices may be applied to the laterally extending arm of said bell crank at different 95 distances from its axis.

6. In a visible writing machine, the combination with a shifting carriage and ribbon vibrator of a bell crank lever located in the longitudinal center of the machine, pivoted upon the carriage and attached to the vibrator, of a second bell crank lever also located in the center of the machine and having an upwardly extending arm connected by a link to the first named bell crank and a horizontally extending arm, and a connection 105 between the latter and the universal bar.

7. In a visible writing machine the combination with a shifting carriage and ribbon vibrator of a bell crank lever located in the longitudinal center of the machine, pivoted 110 upon the carriage and attached to the vibrator, of a second bell crank lever also located in the center of the machine and having an upwardly extending arm connected by a link to the first named bell crank and a horizontally extending arm, a connection between the latter and the universal bar, a third bell crank rocking about the axis of the second mentioned bell crank, a connection between it and the universal bar and a connection between it and the escapement pawl of the machine.

8. In a visible writing machine, the combination with a ribbon vibrator of a bell crank lever having a downwardly extending arm 115

and a laterally extending arm connected to the vibrator, a second bell crank rocking about a fixed axis and having upwardly and laterally extending arms, a link connection 5 between such upwardly extending arm and the downwardly extending arm of the first mentioned bell crank and a connection between the laterally extending arm of the second mentioned bell crank and the universal bar.

10. In a visible writing machine, the combination with a ribbon vibrator of a bell crank lever having a downwardly extending arm and a laterally extending arm connected to the vibrator, a second bell crank rocking about a fixed axis and having upwardly and laterally extending arms, a link connection 15 between such upwardly extending arm and the downwardly extending arm of the first mentioned bell crank; a connection between the laterally extending arm of the second mentioned bell crank and the universal bar, and means for at the will of the operator, varying the distance from the axis of said bell crank at which the connection from the universal bar is applied thereto.

10. In a visible writing machine, the combination with a ribbon vibrator of a bell crank lever having a downwardly extending arm and a laterally extending arm connected to the vibrator, a second bell crank rocking about a fixed axis and having upwardly and laterally extending arms, a link connection 30 between such upwardly extending arm and the downwardly extending arm of the first mentioned bell crank; a connection between the laterally extending arm of the second mentioned bell crank and the universal bar, and means for at the will of the operator, varying the distance from the axis of said bell crank at which the connection from the universal bar is applied thereto.

11. In a visible writing machine, the combination with a vertically shifting carriage and vertically movable ribbon vibrator of a bell crank lever pivoted on the carriage and connected to the vibrator, a second bell crank lever rocking about a fixed axis on the frame, 45 a horizontally disposed link connection between one arm thereof and the first named bell crank and a link connection between the latter arm thereof and the universal bar.

12. In a visible writing machine, ribbon 50 vibrating mechanism comprising the combination of a bell crank lever having seats or recesses in one of its arms, a link connected at its lower end to the universal bar and at its upper end having a projection adapted to engage such recesses, and a pivotal adjusting arm connection with such link connection whereby on movement of said arm the link connection may be engaged with either one of the recesses in the bell crank arm.

65. 13. In a visible writing machine, ribbon

vibrating mechanism comprising a bell crank rocking about a fixed axis and having a laterally extending arm, a link attached at one end to the universal bar and adapted at its other end to engage the laterally extending bell crank arm, means under the control of the operator for engaging said link with said arm at different distances from the axis of the latter and for totally disengaging it therefrom, whereby on actuation of the universal bar the bell crank may be actuated by different leverages to afford variable movement thereof or may remain at rest, for the purpose described.

14. In a visible writing machine, ribbon 80 vibrator mechanism comprising the combination of a bell crank lever, a link connection between one arm thereof and the universal bar, an adjusting arm controlling the distance at which said link connection is applied to the bell crank arm, a link extending from such adjusting arm forwardly, and an adjustable lever in the key board to which the forward end of said link is connected.

15. Ribbon feed mechanism for typewriting machines comprising the combination with rotatable ribbon bobbins mounted below the top of the machine adjacent the side plates thereof upon horizontal axes transverse to the axis of the platen, roller guides 85 located at the top of the machine vertically above the ribbon bobbins and having their axes slightly inclined to the longitudinal center of the machine and a ribbon vibrator located midway between the rollers and in 100 a transverse line slightly in rear of a transverse line passing through the roller guides.

16. In a ribbon feeding mechanism for typewriting machines, the combination of a transverse driving shaft having a bevel pinion thereon and a ribbon bobbin shaft placed at right angles to the first mentioned shaft and having a bearing intermediate its ends and at one end a bevel gear adapted to engage said pinion and at the other a non-circular seat or bearing adapted to receive 110 a ribbon bobbin.

17. In a ribbon feed mechanism for typewriting machines, a pair of ribbon bobbin shafts located adjacent opposite sides of the 115 machine, bearings in which they are seated intermediate their ends, a gear on each shaft on one side of the bearing the opposite end of each shaft being adapted to receive a ribbon bobbin combined with an endwise 120 movable shaft driven from the spring drum and carrying gears respectively adapted to be at will engaged with the respective gears on the ribbon bobbin shafts.

18. In a ribbon feed mechanism for typewriting machines, a shaft having a bearing intermediate its ends and having one end equipped with a driving gear and the other end adapted to receive a ribbon bobbin combined with a driven endwise movable shaft 125 130

having a gear adapted by the endwise movement of the shaft to be thrown into and out of engagement with the gear on the ribbon bobbin shaft.

- 5 19. In a ribbon feed mechanism for typewriting machines, ribbon bobbins adapted to be alternately driven mounted below the top of the machine and adjacent the side plates thereof, ribbon roller guides located above 10 the ribbon bobbins adjacent the respective sides of the machine, the ribbon bobbins being so mounted that the ribbon passes from the outer diameter of each roll to its roller guide and a ribbon vibrator located equi- 15 distant between the roller guides.

20. In a ribbon feed mechanism for typewriting machines, a pair of ribbon spools mounted for rotation upon horizontal shafts, a pair of ribbon roller guides mounted above 20 said shafts and outside of vertical lines drawn through the shafts, the spool being mounted upon the shafts in such relation that the ribbon passes to and from their outside diameters over the guide rollers.

- 25 21. Ribbon feed mechanism for a front strike typewriting machine, comprising the combination of a ribbon vibrator located adjacent the printing point, ribbon guides whose axes are disposed obliquely to the 30 axis of the platen located on each side of the vibrator and in a transverse plane in front of that in which is located the vibrator, and ribbon bobbins located below the guides and from which the ribbon passes 35 upwardly over the guides to the vibrator.

22. Ribbon feed mechanism for a front strike typewriting machine, comprising the combination of a ribbon vibrator located adjacent the printing point, ribbon guides whose axes are disposed obliquely to the 40 axis of the platen located on each side of the vibrator and in a transverse plane in front of that in which is located the vibrator, and ribbon bobbins having axes transverse to 45 the platen of the machine located below the guides and from which the ribbon passes upwardly over the guides to the vibrator.

23. Ribbon feed mechanism for a front strike typewriting machine, comprising the 50 combination of a ribbon vibrator located adjacent the printing point, ribbon guides whose axes are disposed obliquely to the axis of the platen located on each side of the vibrator and in a transverse plane in 55 front of that in which is located the vibrator, and ribbon bobbins adapted to be

alternately driven located below the guides and from which the ribbon passes upwardly over the guides to the vibrator.

24. Ribbon mechanism for a front strike 60 typewriting machine, comprising the combination of a platen, a ribbon vibrator located adjacent the printing point, ribbon guides located on each side of the vibrator in a transverse plane in front of that in which 65 the vibrator is located and ribbon bobbins, located below the plane of the platen, from which respectively the ribbon passes over the corresponding guide to the vibrator.

25. In a ribbon feed mechanism for typewriting machines, a pair of ribbon spools mounted for rotation upon horizontal shafts, a pair of ribbon guides having curved guiding faces mounted above said shafts and outside of vertical lines drawn through the 75 shafts, the spools being mounted upon the shafts in such relation that the ribbon passes to and from their outside diameters over the guides.

26. Ribbon feed mechanism for a front 80 strike typewriting machine, comprising the combination of a ribbon vibrator located adjacent the printing point, ribbon guides having curved faces whose axes are disposed obliquely to the axis of the platen located 85 on each side of the vibrator and in a transverse plane in front of that in which is located the vibrator, and ribbon bobbins located below the guides and from which the ribbon passes upwardly over the guides to 90 the vibrator.

27. Ribbon vibrating mechanism for a front strike typewriting machine, comprising a shifting platen, a ribbon vibrator, means whereby the vibrator is automatically 95 adjusted to the platen when the latter is shifted, a lever acting to throw the vibrator to the printing point, a universal bar, a swinging link extending from the universal bar to said lever and adjustable means under control of the operator for applying the link to said lever at different distances from the axis of the latter to thereby, at will, effect different extents of movement of the vibrator.

In testimony whereof, I have hereunto subscribed my name.

EDWARD B. HESS.
